Knutie E. Bellows
Attorney

UNITED STATES PATENT OFFICE.

JAMES N. HENRY, OF PROVIDENCE, RHODE ISLAND.

CURTAIN ROD AND BRACKET.

Application filed August 30, 1924. Serial No. 735,213.

To all whom it may concern:

Be it known that I, JAMES N. HENRY, a citizen of the United States, residing at Providence, in the county of Providence and State of Rhode Island, have invented certain new and useful Improvements in Curtain Rods and Brackets, of which the following is a specification.

My invention relates to that type of curtain supports wherein the ends of the rod or rods are slidably detachable from the brackets.

The essential objects of my invention are to insure such a complete engagement of the bracket and rod as to prevent accidental disengagement; to afford facility of removal of the rod from the bracket; to prevent rattling of the parts; to enable the brackets to be each struck and bent up from a single blank; and to attain these ends in an inexpensive structure possessing a maximum of strength, and adapted for use in a variety of locations.

To the above enumerated ends primarily my invention consists in such parts and in such combinations of parts as fall within the scope of the appended claim.

In the accompanying drawings which form a part of this specification—

Figure 1 is a fragmentary front elevation of a curtain rod mounted in a pair of brackets embodying my invention,

Figure 2, a section taken on line 2—2 of Figure 1,

Figure 3, a fragmentary plan view of a bracket and rod,

Figure 4, a front elevation of a bracket, and

Figure 5, a detail view of one end of the rod.

Like reference characters indicate like parts throughout the views.

In the form of my invention herein illustrated the rod comprises two telescoping sections 7 with curved end portions, but the rod may be nonsectional or straight if desired. Each rod end is preferably enlarged, as at 8, and is provided near its extremity with an annular groove 9 producing a shoulder 10, a neck 11 and a head 12. Centrally of the disk is a rounded projection 13.

The rod is engageable at its end with brackets. Each bracket 15 is cut and bent

by suitable tools from thin resilient sheet metal blanks. It is preferably oblong having end attaching portions 17 provided with central perforations 18 to receive attaching screws 19. The body portion of the bracket, with which the lugs 17 are integral, extends forwardly of the latter and comprises upper and lower shoulders 22 and 23 supporting an integral face plate 24. This plate has an upright U shaped opening 25 extending to an oblong slot 26 in the shoulder 22 of somewhat greater length than the width of the opening. Flat resilient oppositely disposed fingers 28 in the rear of and parallel with the plate 24 are connected with the plate by rearwardly extending open loop portions 29 integral with the opposite sides of the plate intermediate its ends. The fingers are therefore spaced from the plate 24. Their adjacent free end edges are provided with semi-circular notches 30.

The slot 26 receives the head 12 of the rod whose neck 11 is moved down to the bottom of the opening 25 and the head 12 and shoulder 9 embrace the adjacent portions of the plate 24. In its descent the knob or projection 13 is intercepted by the ends of the fingers 28 which are rearwardly distended thereby until the notches 30 are reached, whereupon the knob snaps into the notches and is embraced therein, so that the rod is insured against accidental escape from the bracket.

I claim:—

In a device of the character described, a curtain rod provided with an annular lateral recess forming a neck and a terminal head, a knob on the end of the rod, a bracket comprising attaching lugs, forwardly projecting walls upon the lugs, one of said walls being provided with a slot, a face plate joining the walls provided with an opening extending to the slot and adapted to receive the neck of the rod, and horizontally disposed inwardly directed lateral resilient fingers spaced from the plate in the rear of the plate comprising open loop portions and provided in their adjacent edges with registering cavities adapted to yieldingly embrace the knob upon the end of the rod.

In testimony whereof I have affixed my signature.

JAMES N. HENRY.
